ELECTRICAL WARP STOP MOTION

Application filed June 27, 1930. Serial No. 464,358.

This invention relates to improvements in electrical warp stop motions and it is the general object of the invention to provide simplified means for connecting the several 5 live electrodes of a warp stop motion capable of operating with a varying number of contact bars.

In my co-pending application Ser. No. 350,401 there is shown a built-tip warp stop motion formed of a plurality of groups of units, the groups being variable in number and substantially similar so that a small or relatively large number of banks of drop wires may be accommodated. Each contact 10 bar has a grounded and a live electrode, and it is necessary to have all of the live electrodes energized regardless of the number of contact bars in use. It is an important object 15 of my present invention to provide a readily expansible connector for the live electrodes so arranged that when additional bars are added their live electrodes may be electrical- 20 ly connected to those already in use.

It is a further object of my present invention to extend the live electrodes beyond those which are grounded and attach them together by means of a longitudinal member passing through them and on which may be strung a plurality of spacers which are of 25 the correct length to hold the extended ends in the same spaced relationship as exists for the main part of the contact bars.

With these and other objects in view which 30 will appear as the description proceeds, my invention resides in the combination and arrangement of parts hereinafter described and set forth in the claims.

In the accompanying drawing wherein a 35 convenient embodiment of my invention is set forth,

Fig. 1 is a top plan view of one end of a warp stop motion having my invention applied thereto,

Fig. 2 is a vertical section on an enlarged scale taken on line 2-2 of Fig. 1,

Fig. 3 is a vertical section on line 3-3, Fig. 2,

Fig. 4 is a perspective view of one end of 50 a contact bar made to cooperate with my invention, and

Fig. 5 is a diagrammatic view showing my invention applied to the use of a smaller number of contact bars than that shown in Fig. 1.

Referring to Figs. 1 and 2, I have shown a 55 loom frame 10 and a whip roll 11 together with a bracket 12 secured in fixed relation to the loom frame. A vertically adjustable bearing member 13 receives the short end 14 of an angle iron the threaded end 15 of which is parallel to the warp and is held in angular relation with respect thereto by means of set screw 16. On the threaded end 15 are front and rear clamping nuts 17, between which lie a plurality of substantially 60 similar spacing and supporting units 18. Located between the units are electric contact bars 19, located preferably above the angle iron, and separator bars 20 located below the angle iron, as shown in Fig. 2. It is sufficient for present purposes to state that the 65 number of units 18 may be varied according to the demands of the warp and that the clamping screws hold the units and their bars as a substantially rigid unitary structure. 70

Each detector bar includes a grounded electrode 21 having its upper and lower edges rounded as at 22 and 23, respectively, and having a rib 24 parallel to the edges and extending longitudinally along its vertical wall 25. The live electrode 26 may be located within and insulated from the grounded electrode. A vertical exposed surface 27 of the live electrode is adapted for engagement 80 with a part of the drop wire D, while other portions of the drop wire engage the rib 24 to effect a lateral movement of the drop wire 85 when the latter falls.

The matter thus far described is substantially the same as that set forth in my afore- 90 said application, the grounded electrodes 21 all being electrically connected to the frame of a loom or other machine by means of angle iron, contact of the bars to the ground being 95 established by the units 18 and the clamping nuts.

In order to electrically connect the live electrodes 26 I extend each electrode as at 40 and provide it with an open slot 41 to receive 100

a bolt 42 having a head 43 and a threaded end 44 on which is a nut 45. Slipped on said bolt is a plurality of electric current conducting sleeves or spacers 46 which, as shown in Figs. 1 and 3, lie between the extended ends of the live electrodes. There will ordinarily be one spacer between adjacent live electrodes, the number of spacers depending upon the number of contact bars. An

10 electric wire 47 may be clamped between a washer 48 located intermediate the nut 45 and one of the end live electrodes. Another washer 49 may be located between the head 43 and the opposite live electrode, if desired.

15 As shown diagrammatically in Fig. 5 there are two live electrodes and a single spacer 46, the latter being of such length as to fit between the live electrodes without deflecting the same when the clamping nuts 17 are in place.

20 If it be desired to expand the width of the stop motion by adding additional bars this may be done by removing one of the nuts 17 and putting in place as many contact bars as are required, after which additional spacers 46 may be strung along the bolt 42 so as to electrically connect each of the live electrodes. The nut 45 will then be tightened to hold the spacers securely against the live electrodes, with the spacers and bolt supported 25 by the live electrodes. The bolt 42 is made long enough to satisfy the needs of the widest motion, but with narrow motions only that part of it is actually used which is needed.

30 35 When the drop wire falls a circuit will be established between the grounded electrode and the corresponding live electrode, whereupon current will flow through the wire 47 along the bolt 42 and establish an external 40 circuit not shown but of the usual type and effective to stop the loom or give other indication that a defect exists in the warp.

From the foregoing it will be seen that I have provided a simple means for electrical- 45 ly connecting the live electrodes and that this means is so constructed as to permit the ready expansion of the motion by the addition of extra contact bars. It will further be seen that the connection between said live elec- 50 trodes is supported by the contact bars so that there is no necessity for aligning the units 18 with the contacts inasmuch as the latter adapt themselves to the unified structure. It will further be seen that a single 55 electrical connection with the bolt 42 suffices to energize all of the live electrodes and that by reason of the open slot 41 a new bar may be slipped longitudinally in position without requiring the removal of the bolt 42 from the 60 original live electrodes.

Having thus described my invention it will be seen that changes and modifications may be made therein by those skilled in the art without departing from the spirit and scope 65 of the invention and I do not wish to be lim-

ited to the details herein disclosed, but what I claim is:

1. In a warp stop motion having a plurality of similar spacing units each positioning an electric contact bar, a live electrode 70 for each bar, a built-up connecting means for the electrodes including a support common to the electrodes and separate contacting elements on the support located between and in contact with the electrodes, there being a unit for each element.

2. In a warp stop motion having a plurality of similar spacing units each positioning an electric contact bar, a live electrode for 80 each bar, a series of contact spacers located transversely of the bars, and means to clamp said spacers to electrodes to electrically connect the electrodes, there being a unit for each element.

3. In a warp stop motion having a plurality of similar spacing units each positioning an electric contact bar, a live electrode for 85 each bar, a set of spacers made of current conducting material, the electrodes and spacers alternating, and means to clamp the spacers and electrodes together to electrically connect the electrodes.

4. In a warp stop motion having a plurality of similar spacing units each positioning an electric contact bar, a live electrode for 90 each bar, a set of current conducting spacers, each electrode having contact with at least one spacer, and means to clamp the spacers and electrodes together to electrically connect the electrodes.

5. In a warp stop motion having a plurality of electric contact bars which may vary in number, a live electrode for each bar, a bolt extending transversely of the bars, a set 105 of current conducting spacers strung along the bolt, and clamping means to hold the electrodes and spacers in electric contact.

6. In a warp stop motion having a plurality of electric contact bars which may vary in number, a live electrode for each bar, a longitudinally extending support transverse of the bars and extending through the electrodes, current conducting spacers separate from and mounted on the support and engaging the electrodes, and means to clamp the spacers together to establish electric contact with the electrodes.

7. In a warp stop motion having a plurality of similar units each positioning an electric contact bar and capable of having additional units added thereto, a support parallel to the units, a live electrode for each bar, and a plurality of contacting elements spaced from and arranged on the support to electrically connect the electrodes, the motion capable of enlargement by the adding of a contact element and a unit for each bar added.

8. In a warp stop motion having a plurality of similar units each positioning an 130

electric contact bar, a live electrode for each bar, a series of current conducting elements to electrically connect the electrodes, there being one more of the units than there are 5 contact bars and one less conducting element than there are bars.

In testimony whereof I have hereunto affixed my signature.

OSCAR V. PAYNE.
